PARKING TIME KEY

William Hugh Fraser, Reno, Nev.

Application December 5, 1938, Serial No. 243,939

14 Claims. (Cl. 70—395)

My invention relates to improvements in a parking time key, and it consists of the combinations, constructions and arrangements hereinafter described and claimed.

5 The business districts in larger cities have parking restrictions and in many instances allot a predetermined time period for a car to remain parked at any given location. It is difficult for a person who has parked his car in a time 10 restricted zone to know exactly when the time period is up and this is true even though a person carries a watch because frequently he either fails to check the time at the moment of parking or he will forget the exact time of parking soon 15 after leaving the car. The result is that the person will come back to the car either sooner than necessary or after the parking time period has elapsed.

The principal object of my invention is to provide a parking time key which is automatic in 20 operation and will warn the driver after a predetermined time period has elapsed. The device includes the use of an automobile ignition key and the mere placing of this key in the 25 automobile lock to start the car, will actuate a member to wind a clock mechanism forming a part of the device. The clock mechanism will be held against functioning so long as the key remains in the lock, but as soon as the key is 30 removed, the mechanism will keep time and when a predetermined period of time has elapsed, the device will automatically give a warning sound that will be heard by the driver. This will warn him that it is time to return to the car. The 35 device employs novel means for controlling the amount of time to elapse before the device will function to give its warning signal.

The device is extremely simple in construction and is also compact so that it may be carried with the other keys or in the pocket. The drawing shows the casing on a large scale for the purpose of more clearly showing the parts, but in reality the mechanism will be made small so that the casing will take up very little additional space. It is possible to place different keys 40 on the device and in this way the article can be used on different ignition locks or for other purposes.

Other objects and advantages will appear in 45 the following specification, and the novel features of the device will be particularly pointed out in the appended claims.

50 My invention is illustrated in the accompanying drawing forming a part of this application, 55 in which

Figure 1 is a vertical section through the device taken substantially along the line 1—1 of Figure 3, parts being omitted for clarity;

Figure 2 is a view similar to Figure 1, but shows the parts in operative position; 5

Figure 3 is a section substantially along the line 3—3 of Figure 1;

Figure 4 is a section substantially along the line 4—4 of Figure 1;

Figure 5 is a rear elevation of the device, portions being shown in section;

Figure 6 is a top plan view of the device; and

Figure 7 illustrates one of the ratchet wheels on a larger scale.

In carrying out my invention, I provide a casing indicated generally at 1 and this casing has a rear face 2 provided with a recess 3 in its outer surface for receiving the handle 4 of an automobile ignition key 5 or other key, see Figures 3 and 5. A screw 6 removably secures the key to 20 the casing and this permits any desired key to be attached to the casing. The shank of the key projects beyond the periphery of the casing and a bar 7 slides along one side of the shank, see Figure 3. The bar is designed to be moved 25 inwardly into the casing when the key is inserted in a lock and the bar contacts with the face 8 of the lock, see Figure 2.

The bar has its inner end provided with a bore 9 for receiving a guide and supporting rod 10 30 that is carried by the casing 1. A coil spring 11 is mounted on the rod and bears against the inner end of the bore 9 so as to yieldingly urge the bar in an outward direction. When the bar is moved inwardly by the insertion of the key 35 into a lock, it will wind up a timekeeping mechanism. This mechanism after operating for a predetermined length of time upon the withdrawal of the key from the lock, will free the bar 7 and the bar will actuate a sound producing mechanism to warn the driver the time is up. I will describe the sound producing mechanism first and then will set forth the particular construction of the timekeeping mechanism. 40

The bar 7 has a rack 12 on its underside and 45 this rack meshes with a ratchet wheel 13, see Figure 4, mounted on a shaft 14 that is carried by the rear wall 2. The ratchet wheel 13 is so designed so as not to impart rotation to a gear 15 during the insertion of the key in the lock and 50 the retraction of the bar. The ratchet wheel 13 is shown in Figure 7 in mesh with the rack 12. The bar 7 is seen from the same side as shown in Figure 5. The wheel consists of a ring gear portion 13a meshing with the rack 12 and riding over 55

a hub portion 13b when the bar is moved inwardly in the direction of the arrow *a*. The hub has wedge-shaped recesses 13c with balls 13d that will lock the hub to the ring gear when the bar 7 moves outwardly under the force of the spring 11. The hub 13b is connected to the gear 15 by means of a sleeve 16a, see Figure 4, and the gear 15 meshes with a gear 16 that is operatively connected to a disc 17.

10 Figure 5 shows the disc 17 as being of a large diameter and carrying spring members 18 that are designed to be rapidly moved over projections 19 carried by the casing. This will create a rattling noise that will give a warning signal. It is possible to use weights (not shown) in place of springs 18 and these weights can be pivoted to the disc and will fly out by centrifugal force when the disc is rotated so as to successively strike the projections 19 and give a warning signal. It will be seen from this construction that when the bar 7 is released by a mechanism hereinafter described and is moved outwardly by the spring 11, then the ratchet wheel 13 will be rotated and will rotate the gears 15 and 16 and cause the disc 17 to rotate and give the warning signal.

I provide novel means for locking the bar 7 against outward movement until a predetermined time period has elapsed. This means includes means for holding the bar 7 and also a clock mechanism. The clock mechanism is shown in Figures 1 and 4. The bar 7 has a rack 20 on its upper side meshing with a second ratchet wheel 21, see Figure 4, similar in construction to the ratchet wheel 13. When the bar 7 is moved inwardly it will rotate the wheel 21 for winding a main spring 22 of the clock mechanism. When the bar is moved outwardly by the spring 11, the rotating ratchet wheel 21 will have no effect upon the spring 22 and will permit it to return to its unwound state ready for the next operation. Figure 4 shows the ratchet wheel 21 mounted on a shaft 23 that is carried by the rear wall 2 of the casing. A large gear 24 is mounted on the shaft 23 and the coil spring 22 connects the gears 21 and 24 together so that the gear 24 is placed under spring tension when the main spring 22 is wound by the rotation of the ratchet wheel 21. The gear 24 meshes with another gear 25 which in turn is rotatably mounted on the shaft 16. An escapement wheel 26 of standard watch construction is connected with the gear 25 and is controlled in its movement by a standard escapement lever 27. The lever 27 is actuated by a balance wheel 28 and a hair spring 29 in the usual manner of clock mechanisms.

55 A small gear 30 is connected with the gear 24 so as to rotate therewith and meshes with a large gear 31 which in turn is connected to a disc 32 by means of a sleeve 33. The gear 31, the disc 32 and the sleeve 33 are rotatably mounted on a shaft 34. A time indicating lever 35 is also mounted on the shaft 34 and a coil spring 36 bears against a head of the shaft 34 and frictionally holds the lever against the disc 32, for causing 60 the lever to rotate with the disc. Figure 1 shows the lever extending through a slot 37 in the casing and Figure 6 shows the periphery of the casing, adjacent to the slot, provided with time-indicating numbers 38. These numbers indicate time 65 intervals from 0 up to 60 minutes. It is obvious that the numbers may be changed at will to indicate other time periods.

In Figure 1, I show a spring actuated catch 39 for holding the bar 7 in retracted position. The 75 bar has a notch 40 for receiving the catch when

the key 5 is retracted from the lock and the bar has moved a sufficient distance to align the notch with the catch. So long as the key remains in the lock, the bar 7 will be retracted to a position where the notch 40 will be moved beyond the catch 39, see Figure 2. A stop arm or finger 41 is carried by the bar 7 and contacts with the balance wheel 28, see Figure 2, for preventing the rotation of the wheel so long as the key remains in the lock. When now the key is removed from the lock, the bar 7 will be initially moved by the spring 11 until the catch 39 enters the notch 40. The bar is prevented from further movement until the designated time period has elapsed. Figure 3 shows the catch 39 provided with a spring 39a for yieldingly urging the catch against the bar. The opposite end 39b of the catch extends up to a position adjacent the disc 32, see Figures 1 and 2. The time-indicating lever 35 has a projection 42 for contacting with the end 20 39b when the lever reaches the "0" reading on the time scale 38. This will free the catch from the notch and will permit the spring 11 to immediately move the bar back into starting position.

25 From the foregoing description of the various parts of the device, the operation thereof may be readily understood.

The key 5 is used in the ordinary manner and when the key is inserted into the lock, the bar 7 will be retracted. This rearward movement of the bar will cause the ratchet wheels 13 and 21 to rotate. As already stated, the ratchet wheel 13 in rotating will not rotate the disc 17. The ratchet wheel 21, however, in rotating, will wind the main spring 22 which in turn will act as a spring motor and furnish the power for running the clock mechanism. The bar 7 carries the finger 41 which will engage with the balance wheel 28 and prevent the wheel from operating so long as the key remains in the lock. The clock mechanism will therefore not function until the key is removed. It will be noted from Figure 2 that when the bar 7 is entirely retracted, the notch 40 will be held out of registration with the spring 11 actuated catch 39. This is to permit the bar to remove the finger 41 from the balance wheel as soon as the key is removed from the lock.

50 Before the key is removed from the lock, however, the driver manipulates the time-indicating lever 35 along the slot 37, see Figure 6, into a position where it will indicate the time which is to elapse before the device will give a warning sound. For example, if the parking time limit is thirty minutes in the zone where the car is parked, the lever 35 will be moved opposite the number 30 or if the driver wishes to be warned five minutes ahead of time, the lever can be moved midway between the numbers 20 and 30. The spring 36 will permit this setting of the lever and the disc 32 will not be rotated. When the lever is freed, the spring will hold it against the disc so the lever will slowly turn with the disc while the clock mechanism is functioning. If the driver does not wish to set the device, in order to have it warn him at a later time, he can merely permit the lever 35 to remain in a position opposite the "0" number when removing the key from the lock. The projection 42 will then continue to engage with the catch 39 and hold it in inoperative position. The bar 7 will therefore immediately move into its outermost position and the device will therefore not be able to function at a later time.

70 After the lever has been set for a certain time, 75

it will slowly move to the "0" position and the driver can in this way tell how much time he has left. The lever is moved by the disc 32 and when the lever reaches "0" position, the projection 42 will free the catch 39 from the bar 7. This will permit the bar to be instantly moved outwardly by the spring 11 and to rotate the ratchet wheel 13 and the disc 17. The springs 18, carried by the disc, will rattle over the projections 19 and give a warning sound that will inform the person carrying the device that the time period has elapsed. The device will be automatically reset when the key is again placed in the lock and the lever 35 will remain in "0" position until it is again manually moved into a position opposite the desired number prior to taking the key from the lock. Should the driver return to the car before the warning mechanism has operated, it is necessary that the lever 35 be manually moved into "0" position before the key is again inserted into the lock. This will permit the catch 39 to free the bar 7 and then when the key is reinserted in the lock, the retraction of the bar 7 will again completely wind the spring 22. If the driver does not move the lever into the "0" or "off" position to free the bar prior to inserting the key into the lock, the bar 7 will not be repressed and the spring 22 will not be wound completely and therefore a subsequent removal of the key from the lock will leave a partly wound spring without sufficient tension to operate the clock mechanism for the full time period.

Different keys may be attached to the casing and this adapts the device to be used with different cars or for other purposes. The casing 1 may be made extremely compact and the operating parts may be made very small. The entire device should therefore not occupy much more space than occupied by the key itself. This will permit the device to be carried in a key container, if desired or in a pocket or pocket book.

While I have shown only the preferred form of my invention, it should be understood that various changes or modifications may be made within the scope of the appended claims without departing from the spirit of the invention.

I claim:

1. A parking time key having a timekeeping mechanism, a bar actuated by the insertion of the key in a lock for winding the mechanism, means for holding the bar retracted when the key is removed from the lock, means for producing a warning sound, means actuated by the mechanism for releasing the bar after a predetermined time interval, and a spring for returning the bar to initial position, said bar in moving, actuating said sound producing means.

2. A parking time key having a timekeeping mechanism, a bar extending alongside of the key and being moved when the key is inserted in a lock, the movement of the bar winding the mechanism, said mechanism functioning when the key is withdrawn from the lock, a spring for moving the bar back into starting position, a catch for holding the bar in retracted position, means carried by the mechanism for freeing the bar after a predetermined time interval, and an audible signal actuated by the return movement of the bar.

3. In a parking time key, a timekeeping mechanism, a bar for winding the mechanism, a spring for returning the bar to starting position, means for holding the bar against return movement, means actuated by the mechanism for releasing the bar-holding means after a predetermined

time interval and including adjustable means for varying the length of the time interval at will.

4. In a parking time key, a timekeeping mechanism, a bar movable into a retracted position for winding the mechanism, a catch for holding the bar retracted, a lever movable by the mechanism for freeing the catch from the bar after a predetermined time interval, said lever being manually adjusted for varying the amount of time necessary to elapse before freeing the catch, a spring for returning the bar to initial position when the bar is freed, and a warning signal actuated by the return movement of the bar.

5. In a parking time key, a timekeeping mechanism, a bar movable into a retracted position for winding the mechanism, a catch for holding the bar retracted, a lever movable by the mechanism for freeing the catch from the bar after a predetermined time interval, said lever being manually adjusted for varying the amount of time necessary to elapse before freeing the catch, a spring for returning the bar to initial position when the bar is freed, and a warning signal actuated by the return movement of the bar, said lever being movable into a position for immediately freeing the bar.

6. A parking time key having a casing, a timekeeping mechanism mounted therein, a bar slideable along one side of the key and being movable into retracted position when the key is inserted in a lock, a spring for returning the bar to starting position, said bar when retracted winding the mechanism, means carried by the bar for preventing the mechanism from functioning so long as the key remains in the lock, a catch for holding the bar in retracted position after the key has been removed from the lock and after the bar has moved a slight distance to free the clock-stopping mechanism and permit it to function, a lever for freeing the catch, said lever being slowly moved by the mechanism and being manually adjusted to vary the time period for freeing the catch, said casing having numbers associated with the lever for indicating the time to elapse before the catch is freed from the bar, and a warning signal actuated by the return movement of the bar to starting position.

7. In a device of the type described, a casing, a time keeping mechanism mounted therein, a spring-pressed bar for winding the mechanism, a key removably secured to the casing and lying alongside the bar, whereby the bar will be repressed when the key is inserted in a lock and will wind the mechanism, said mechanism functioning when the key is removed from the lock, means for preventing the return movement of the bar, means actuated by the mechanism for freeing the bar holding means, and a warning signal operatively connected to the bar and being actuated by the moving bar after a given time interval.

8. In combination, a timekeeping mechanism, a key, a spring-pressed bar moved by the face of a lock when the key is inserted in the lock, the movement of the bar winding the mechanism, means associated with the bar for preventing the mechanism from operating, a warning signal, said mechanism functioning when freed by the last-named means due to the removal of the key and the return of the bar, said mechanism actuating the warning signal after a predetermined time interval.

9. The combination with a key insertable into a lock, of a timekeeping mechanism associated therewith, means for winding the mechanism, means actuated by the withdrawal of the key for

starting the mechanism to operate, signalling means, and means actuated by the mechanism after a predetermined time interval for operating the signalling means.

5 10. The combination with a key insertable into a lock, of a timekeeping mechanism associated therewith, means for winding the mechanism, means actuated by the withdrawal of the key for starting the mechanism to operate, signalling

10 means, and means actuated by the mechanism after a predetermined time interval for operating the signalling means, and means for varying the time period between the withdrawal of the key and the operation of the signalling means.

15 11. A parking time key having a timekeeping mechanism, means for winding the mechanism, means actuated by the withdrawal of the key for starting the mechanism to operate, signalling means, means actuated by the mechanism after a predetermined time interval for operating the signalling means, said signal operating means including a manually adjustable hand for varying the elapsed time period.

12. A parking time key comprising a casing, a
25 key removably secured thereto, a timekeeping mechanism housed within the casing, a spring-pressed bar slidably disposed alongside of the key and being moved when the key is inserted into a lock, the inward movement of the bar winding
30 the mechanism, a catch for holding the bar retracted when the key is removed from the lock, an adjustable release for the catch and being moved by the mechanism to free the catch after a predetermined time interval, and signalling
35 means operated by the moving bar during the return of the bar to normal position.

13. A parking time key comprising a casing, a key removably secured thereto, a timekeeping

mechanism housed within the casing, a spring-pressed bar slidably disposed alongside of the key and being moved when the key is inserted into a lock, the inward movement of the bar winding the mechanism, a catch for holding the bar retracted when the key is removed from the lock, an adjustable release for the catch and being moved by the mechanism to free the catch after a predetermined time interval, and signalling means operated by the moving bar during the 10 return of the bar to normal position, said adjustable release consisting of a lever moved by the mechanism, said casing having a slot for exposing the free end of the lever, and numbers placed on the casing and disposed along the slot for 15 indicating elapsed time.

14. A parking time key comprising a casing, a key removably secured thereto, a timekeeping mechanism housed within the casing, a spring-pressed bar slidably disposed alongside of the 20 key and being moved when the key is inserted into a lock, the inward movement of the bar winding the mechanism, a catch for holding the bar retracted when the key is removed from the lock, an adjustable release for the catch and being 25 moved by the mechanism to free the catch after a predetermined time interval, and signalling means operated by the moving bar during the return of the bar to normal position, said adjustable release consisting of a lever moved by the mechanism, said casing having a slot for exposing the free end of the lever, and numbers placed on the 30 casing and disposed along the slot for indicating elapsed time, said lever when placed in "zero position", holding the catch free of the bar for 35 permitting the bar to return to normal position the instant the key is removed from the lock.

WILLIAM HUGH FRASER.
